UNITED STATES PATENT OFFICE.

JOSEPH EDOUARD TOURANGEAU, OF MONTREAL, QUEBEC, CANADA.

NON-SLIPPING UNDERPIECE FOR SURFACE-COVERINGS.

1,234,827.

Specification of Letters Patent. Patented July 31, 1917.

Application filed February 19, 1917. Serial No. 149,643.

To all whom it may concern:

Be it known that I, JOSEPH EDOUARD TOURANGEAU, of 673 Durocher street, in the city and district of Montreal, in the Province of Quebec, in the Dominion of Canada, manager, have invented certain new and useful Improvements in Non-Slipping Underpieces for Surface-Coverings; and I do hereby declare that the following is a full, 10 clear, and exact description of the same.

The invention relates to improvements in non-slipping under piece for surface coverings as described in the present specification and illustrated in the accompanying drawings 15 that form part of the same.

The invention consists essentially of the novel arrangement and the relations of the top and bottom of the under piece with the covering and surface, whereby the said covering spread on the surface is immovable 20 on pressure being brought to bear thereon.

The objects of the invention are to devise a means of preventing the accidental slipping of table and floor coverings and thereby avoid danger to both property and persons, particularly in regard to the slipping 25 of rugs on hardwood floors, to provide an article that will be equally efficient for luxurious and less costly floor and table coverings, and generally to insure cheapness in 30 production and serviceability and durability, in use.

In the drawings, Figure 1 is a perspective view of a floor rug turned over at one 35 end to disclose the under piece.

Fig. 2 is a cross sectional view of rug, under piece and flooring.

Fig. 3 is a sectional view of another form of underpiece.

Like numerals of reference indicate corresponding parts in each figure.

Referring to the drawings, the bottom layer 1 of the underpiece is made of painted oiled or varnished textile material though 45 it is not necessary it should be a textile so covered, as there are other materials, which

will answer the purpose, such as genuine leather or other natural or non-woven stuffs, however for the purposes of this invention leatherette and table oil cloth have been chosen to explain its usefulness and the general method of making it up. When leatherette is used it is preferably pebbled, so as to create a better gripping surface than an absolutely smooth surface. 50 55

The middle layer 2 is a suitable wadding and the top layer 3 is a cotton or other cloth covering.

These layers are preferably bound around with the binding 4 and throughout quilted 60 by the stitching 5.

In Fig. 3 the layer 6 similar to the layer 1, is secured on the bottom side of a felt paper or other board or paper layer 7.

The rug 8 illustrated in the drawings 65 shows one use of the under piece and a very important use, as so many accidents happen from the sudden slip of a rug on a hard wood floor, when stepped on accompanied by the consequent upsetting of the person. 70 Now with the underpiece described the step on the rug is not accompanied by a slip as no matter how quick and heavy the step may be the gripping properties of the said underpiece are sure and positive. 75

The middle layer of wadding is preferably treated to make it a protector for the rugs or other coverings against moths, thereby providing in this rug another useful purpose, which though known before in 80 underpieces for floor coverings has not been used with a non-slipping article.

The use of this for table or shelf coverings will be readily understood and it is not necessary herein to elaborate on its 85 many applications, sufficient to say that any covering for the whole or part of a smooth surface can be made perfectly secure, when spread over the underpiece as described.

Many changes may be made in the way 90 of making up this article from the manner herein shown, without departing from the

spirit of the invention, so long as they remain within the claims for novelty following in the elements covered.

What I claim is:—

- 5 1. In a non-slipping underpiece for surface coverings, a layer of leatherette, an upper layer of textile material, a middle layer of wadding material and suitable binding.
- 10 2. In a non-slipping underpiece for surface coverings, a bottom layer of painted

and treated textile material, an upper layer of textile material, a middle layer of wadding material, a binding around said layers and stitching quilting said layers together. 15

Signed at the city of Montreal, Quebec, Canada, this 15 day of February 1917.

JOSEPH EDOUARD TOURANGEAU.
